MATERNITY PANTIE

Pauline E. Rosenblatt, Cleveland, Ohio

Application August 24, 1946, Serial No. 692,752

1 Claim. (Cl. 2—224)

1

This invention relates to an improved pantie designed particularly, though not exclusively, for prospective mothers.

The general object of the invention is the provision of a pantie or wearing apparel which adjusts itself to the varying figure of the wearer and possesses the comfort and general appearance of ordinary wearing apparel of fixed proportions.

Another object of the invention is the provision of a pantie or wearing apparel of the above class having front and rear sections constructed so that the front section stretches substantially more than the rear section and readily contracts to normal form, thus insuring close and comfortable fit to the varying figure of the wearer.

A further object of the invention is the provision of a pantie or wearing apparel of the above class having a front section constructed with substantially stretchable top and bottom edges and reenforced, non-stretchable side edges for close and comfortable fit of the front section to the varying figure of the wearer and, in addition, having a stretchable rear section with a circumferentially reenforced, non-stretchable edge lining for close and proper fit without pressure and discomfort to the wearer.

Still another object of the invention is the provision of a pantie or wearing apparel of the above class with a front section constructed of a panel made of stretchable material and flexible bands of similar material secured to the top and bottom edges of the panel with the flexible bands shorter in length than the said top and bottom edges, secured to said edges in partly stretched condition for ample fullness and close and comfortable fit of the front section panel over the varying figure of the wearer.

In addition, the invention has certain other marked superiorities which radically distinguish it from presently known pantie constructions. These improvements embodying certain novel features of construction are more clearly set forth in the following specification and the appended claim; and a preferred embodiment of the invention is hereinafter shown with reference to the accompanying drawing forming part of the specification.

In the drawing:

Fig. 1 is a perspective view of the maternity pantie shown applied to a female figure;

Fig. 2 is a front perspective view of the maternity pantie;

Fig. 3 is a rear perspective view of the maternity pantie;

2

Fig. 4 is a plan-view of the several blanks forming the pattern of the maternity pantie;

Fig. 5 is a fragmentary plan-view of the front panel and flexible band prior to securing the band in partly stretched condition to the front panel; and

Fig. 6 is a fragmentary plan-view of the front section showing the band attached to the front panel.

Referring now in detail to the drawing, the open-sided maternity pantie 2 is made of suitable knitted material capable of stretching to a great extent in one direction and readily resuming its normal contracted form. This pantie embodies a front section 3, a rear section 4 and a crotch member 5. Front section 3, which is designed to cling snugly to the front of a wearer and stretch substantially to adjust itself to the varying figure of a prospective mother, embodies a single panel 6 cut and shaped as represented in Fig. 4. The panel, which is substantially stretchable only in lateral direction, has its marginal edges 7 and 8 constituting the normal outer side edges of front section 3, cut to extend in upwardly converging lines and has its marginal edges 9 and 10, constituting the leg portions of the front section, cut on lines curving inwardly of the fabric in concave fashion so as to intersect each other at an obtuse angle. The thus shaped panel has its marginal edges 7 and 8 reenforced by tape or other suitable material and has attached to its top marginal edge 11 a longitudinally stretchable band or strip 12 of knitted material. Strip 12 is shorter than top edge 11, is folded on partly stretched condition around this top edge and sewn thereto to provide the desired fullness for a comfortable fit of front section 3 over the varying figure of a prospective mother. The marginal edges 9 and 10, which constitute the leg portions of the front section, have attached thereto complementary longitudinally stretchable bands or strips 14 and 15 which are also made of knitted material and shorter than the respective marginal edges 9 and 10. These strips, in partly stretched condition, are sewn to edges 9 and 10 to provide the desired fullness of the lower portion of section 3.

The rear section 4, which is constructed of complementary sections 16 and 17 sewn together at their opposed edges 18 and 19, is shaped to include downwardly diverging side edges 20, 21 and a V-shaped bottom edge 22 including in its central area an inverted V-shaped cutout 23. All edges of rear section 4 are reenforced by tape or other suitable material. The thus constructed

front and rear sections 3 and 4 are connected with each other by the crotch member 5. This crotch member, which, as shown in Fig. 4, is of trapezoidal outline, is made of a double layer of knitted material of the type described above. Crotch member 5 has one of its parallel edges, marginal edge 24, sewn to the sides of the inverted V-shaped central cutout 23 of rear section 4, and the other one of its parallel edges, marginal edge 25, sewn to front panel 6 adjacent the point of intersection of its marginal edges 9 and 10 and, in addition, sewn to the opposed inner edges 26 and 27 of bands or strips 14 and 15. This construction and attachment of the crotch member imparts thereto the necessary fullness and make the crotch member more smoothly conform to the body of the wearer.

The thus constructed pantie has the lower outer edges of the front and back sections releasably and yieldingly secured to each other by fastening means 26', 27' effecting yielding clutching of the thighs of a person wearing the pantie, without excessive upward pull in the crotch and yielding stretching of the crotch member to avoid its wrinkling and insure proper absorption of body perspiration and secretion by the crotch member.

To effect proper support of the pantie on the body of the wearer, the front and rear sections have their top portions yieldingly and releasably connected with each other by adjustable tie members 28, an arrangement which also permits easy and quick adjustment of the crotch member in personal use, after opening of one of the fastening means so that comfort and ease are assured.

Having thus described my invention what I claim is:

A maternity pantie comprising a front panel of knitted material having outside edges extend-

ing in upwardly converging lines and two arcuate bottom edges converging at their adjacent ends downwardly, longitudinally stretchable strips of knitted material secured in stretched condition and slightly spaced from each other to the unstretched arcuate bottom edges of said front panel, a back panel having a re-enforced, non-strechable top edge, a crotch member extended between the front and rear panels and connected with the central portions of said front and rear panels and the opposed side edges of said longitudinally stretchable strips, a longitudinally stretchable, folded top strip of knitted material secured in stretched condition to the unstretched top edge of said front panel, yielding strips connecting the ends of said top strip with the ends of the re-enforced top edge of said back panel, and strip-like means connecting the lower ends of the front panel adjacent the ends of the longitudinally stretchable strips to the adjacent edges of the rear panel.

PAULINE E. ROSENBLATT.
